UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

METALLIC STRUCTURE FOR RAILWAY CARS.

Application filed June 7, 1926. Serial No. 114,246

Reference is made to the accompanying drawings, which illustrate the preferred form of the invention, though it is to be understood that the invention is not limited to the

5 exact details of construction shown and described, as it is obvious that various modifications thereof within the scope of the claims will occur to persons skilled in the art.

10 My invention relates to the construction of railway cars and more particularly to metal end structures or walls for railway cars made of one or more metallic plates or panels formed with integral reinforcing, stiffening and bracing corrugations or embossments. 15 However, this device may be incorporated in the construction of car side walls, floors, roofs or doors used in connection with railway cars of various types.

10 It is well known that the end walls of railway cars are more likely to be broken or otherwise injured than the side walls. This is due to the inertia thrusts and pressures caused by the shifting of the cargoes when the train starts or stops. These thrusts may be local, 25 tending to distort the end in some particular spot, as, for example, when a piece of piping or lumber shifts lengthwise imparting a blow against the end wall of the car; or there may be a general tendency to break out the end 30 wall as a whole or tear it away from the framing. For the purpose, therefore, of greater strength and durability, car ends have been constructed of metal plates corrugated or 35 formed with ribs to impart the desired strength, rigidity and resiliency.

One of the principal objects of my invention is to provide a corrugated or embossed metallic end structure for railway cars in which the corrugations or embossments have 40 a configuration and arrangement that impart to the structure a maximum capacity for resisting cargo thrusts, both local and general, and with sufficient resiliency to prevent permanent distortion due to the thrusts of 45 the loads, with a minimum weight of metal. It is important that structures of this sort should be as light as is possible, consistent with strength and durability, both for reasons of economy in manufacturing cost and 50 also to keep the weight of the car at a minimum.

A further object is to provide a corrugated metallic wall element that is practically possible to manufacture. A further object is to 55 provide a metallic wall element with corruga-

tions or embossments that resist to a greater degree torsional stresses, as well as brace the element, and the car end against diagonal side thrusts or weaving.

The combination of the embossments, ribs 60 or corrugations comprising the reinforcement formed in the metallic plate is disclosed and claimed in my separate application for patent, Serial No. 55,207, filed September 8, 1925, and this application for patent discloses and claims the specific advantages and constructions when such a reinforced vertical plate is applied to a car with the corrugations or reinforcements positioned vertically or substantially so, i. e., extending 65 from adjacent the floor of the car (or end sill) to adjacent the roof (or end plate.) The metallic reinforced plates comprising the wall are usually connected along vertical lines, and the middle plate or plates may be 70 made of thicker metal than those adjacent the side of the car and the corrugations in the middle of the car end wall may be made stronger than those elsewhere by being made deeper or wider or both. Also the corrugations in the middle of the car end wall may 75 be made longer to eliminate any flat space between the upper end of the corrugations and the end plate or roof of the car.

The maximum pressure and stress on a 80 car end wall is about two feet above the floor and adjacent the middle of the car. The corrugations are a series of parallel beams and when positioned vertically the lower 85 ends of these beams are supported by the underframe which is the backbone of the car and the upper ends are supported by the end plate. A beam should have its maximum strength adjacent its point of maximum stress, therefore, I prefer to have the strongest 90 part of the individual corrugation, as well as the entire end wall, about two feet from the floor or about one-fourth the length of the corrugation.

Like characters of reference designate like parts.

The end wall structure shown in the above 35 figures comprises a panel composed of a corrugated metal plate or plates.

Referring to Figs. 1 and 2. The corrugated plates 1, 2 and 3 extend across the car from top to bottom and are formed with 40 integral flanges 4 along the vertical edges which overlap and are secured to the side walls 5 of the car by any suitable means.

The top edge of the end wall is secured 45 beneath the fascia boards 7 and the meeting edges of the plates overlap and are secured together by rows of rivets 8 and the lower edge of the end wall is secured to the end sill 9.

Figs. 3 and 4 show the invention applied to 50 a gondola type of car, wherein only one plate 12 is used to form the end panel which extends from side to side of the car and is provided along the vertical edges with flanges 13 which overlap and are secured to the side walls 14 by any suitable means. The top edge of the plate is secured to the top chord 15 by rivets 16, while the lower edge is secured by rivets 17 to the end sill 18.

While the corrugations are shown pressed 55 outwardly, it is understood that the corrugations may be pressed inwardly, or partially inwardly and partially outwardly from the original plane of the plate. The plates or panels may be applied to any type of rail-way car.

Figs. 5 to 9 inclusive show the preferred 60 form wherein the plate 30 is provided with a plurality of major corrugations 31 with preferably flat apices 36 which are spaced apart distances substantially equal to their respec-

tive widths and the part 33 of the plate between the major corrugations are also preferably flat so that the configuration (see Fig. 7) is symmetrical in cross section about a line midway between the outermost portions of 70 these major corrugations, which line is the neutral axis of the section. Such a section is very strong on account of the amount of metal positioned away from the neutral axis and is also relatively rigid. These major 75 corrugations 31 decrease in width toward their opposite ends, and the apices change from a flat to an arcuate configuration. The metallic plate is also provided with a plurality of pairs of aligned minor corrugations 80 32 which lie between adjacent major corrugations 31 with their inner ends preferably terminating into the plate adjacent each other and with their outer ends terminating into the plate in line with the outer ends of the 85 major corrugations.

The outer ends of the minor corrugations 32 have arcuate apices and the part of the plate between these outer ends of the minor corrugations and the outer ends of the major corrugations are also arcuate so that they 90 form a cross section of sinuous configuration, and, furthermore, the outer ends of the minor and major corrugations are of the same width and spaced apart distances substantially 95 equal to their respective widths so that they form a contiguous sinuous configuration (see Fig. 9) symmetrical in cross section about a line midway between the outermost portions of the corrugations, which line is the neutral axis of the section. Such a section is very 100 resilient and has a spring like action under load, and, furthermore, produces a very strong section for the amount of metal used. The minor and major corrugations merge into the plane of the plate by means of terminal portions 46 of any desired formation. By such an arrangement a corrugated metallic plate is provided which is relatively rigid adjacent the floor of the car and relatively 105 resilient adjacent the opposite end portions of the corrugations.

Figs. 16, 17 and 18 are detailed enlargements of portions of a plate 30 on lines 7, 8 and 9, respectively, of Fig. 5.

Fig. 16 shows the relatively wide flat apices 110 36 formed by the major corrugations 31. The sloping sides 37 and the curved portions 38 connect the flat apices 36 to the original plane 35 of the plate.

Fig. 17 shows the minor corrugations 32 pressed outwardly between the major corrugations 31.

Fig. 18 shows the corrugations and uniform form convergence of the major and minor corrugations just before merging into the original plane 35 of the plate 30.

Figs. 10, 11 and 12 are detailed enlargements of a modified form of corrugation similar to Figs. 16, 17 and 18 wherein the 130

major corrugations have arcuate apices 40 and the portions of the plate between the major corrugations is also of arcuate configuration.

5 Fig. 11 shows the minor corrugations 32 pressed outwardly between the major corrugations 31 midway between the center and termination of the corrugations at 34.

10 Fig. 12 shows the contiguous and uniform convergence of the major and minor corrugations just before merging into the original plane 35 of the plate 30.

15 Figs. 13, 14 and 15 are detailed enlargements of a modified form of corrugation similar to Figs. 16-18 and 10-12 wherein the corrugations are truncated.

The flat apices are joined by sloping sides and curves.

20 Fig. 13 shows the relatively wide flat apices 42 formed by the major corrugations 31. The sloping sides 43 and the curved portions 44 join the flat apices of the corrugation to the original plane 35 of the plate 30.

25 Fig. 14 shows the minor corrugations 32 pressed outwardly between the major corrugations 31.

30 Fig. 15 shows the contiguous and truncated convergence of the major and minor corrugations just before merging into the original plane 35 of the plate 30.

35 The major corrugations are preferably of uniform width for a short distance adjacent their middle to provide greater strength for a greater portion of the plate and also to facilitate the changing of the forming dies when it is desired to increase or decrease the length of the corrugations or embossments.

40 A plate provided with a plurality of contiguous narrow corrugations possesses a considerable amount of elasticity and when struck a blow deflects readily and regains its shape without distortion, whereas a plate provided with wide flat corrugations, though better able to carry quiescent loads, has not the resiliency of the former and is more readily distorted when struck a blow.

45 It is, therefore, desirable to design a plate that possesses great strength to withstand the sudden impact loads or blows, with sufficient 50 resiliency to resist distortion.

This application is confined to the construction wherein the minor corrugations merge with the major corrugations, whereas in my application Serial No. 595,634, filed 55 October 19, 1922, I have shown and claimed a construction wherein the major corrugation is split into two or more minor corrugations.

60 I have described and claimed the corrugations as being that portion of the reinforcement between the terminations or between lines corresponding to 9-9 in Fig. 5. The terminations are the conical or pointed portions, such as 46 in Fig. 5.

65 This is a continuation in part of my application Serial No. 55,207 filed September

8, 1925, which is a division of my application Serial No. 595,634, filed October 19, 1922.

I claim:

1. A wall structure for a railway car comprising a plurality of metallic plates secured together along vertical lines, each plate provided with a plurality of parallel vertical major corrugations decreasing in width towards the terminal thereof adjacent the edges of said plate, a plurality of minor corrugations lying in a plane between said major corrugations, said minor corrugations merging from the plane of said plate at the center thereof and increasing in width and depth towards the terminals adjacent the edges of said plate. 75

2. A wall structure for a railway car comprising a plurality of metallic plates secured together along vertical lines, each plate provided with a plurality of major and minor vertical corrugations, said major corrugations projecting from the original plane of said plate forming a uniform cross section with flat apices diminishing in width towards the end of said corrugations where said major and minor corrugations merge and become contiguous and of a sinuous formation. 85

3. A wall structure for a railway car comprising a plurality of metallic plates secured together along vertical lines, each plate having a plurality of major and minor vertical corrugations, terminating within the plate, said major corrugations formed with flat apices decreasing in width toward the ends of said corrugations, said minor corrugations positioned between said major corrugations merging from substantially the center and the plane of the plate, and increasing in depth and width until they merge with said major corrugations to form a contiguous configuration of uniform cross section. 95

4. A wall structure for a railway car comprising a plurality of metallic plates secured together along vertical lines, each plate having a plurality of major and minor vertical stiffening corrugations of varying cross sections throughout the greater portion of their length but merging together forming a cross section uniform in depth, width and shape symmetrical about a line midway between the outermost portions of the corrugations. 105

5. A wall structure for a railway car comprising a plurality of metallic plates secured together along vertical lines, each plate provided with a plurality of major and minor vertical corrugations, said major corrugations being widest, contiguous and symmetrical and provided with flat apices diminishing in width toward the end of said corrugation where said major and minor corrugations merge and become contiguous, symmetrical and parallel for a short distance just before merging into the original plane of the plate. 120

6. A wall structure for a railway car comprising a plurality of metallic plates secured 125

together along vertical lines, each plate having a plurality of major and minor vertical corrugations terminating within the plate, said major corrugations decreasing in width toward the ends, said minor corrugations positioned between said major corrugations merging from the plane of the plate and increasing in depth and width until they merge with said major corrugations to form an arcuate contiguous configuration of uniform cross section.

7. A wall structure for a railway car comprising a plurality of metallic plates secured together along vertical lines, each plate having a plurality of sinuous and contiguous major and minor vertical corrugations terminating within the plate, said major corrugations decreasing in width toward the ends, said minor corrugations positioned between said major corrugations merging from the plane of the plate and increasing in depth and width until they merge with said major corrugations to form a sinuous and contiguous configuration of uniform cross section.

8. A wall structure for a railway car comprising a plurality of metallic plates secured together along vertical lines, each plate having a plurality of major and minor vertical corrugations terminating within the plate, said major corrugations being parallel, contiguous, symmetrical and widest adjacent one of their ends and diminishing in width toward their ends, said minor corrugations positioned between said major corrugations merging from the plane of the plate, and increasing in depth and width until they merge with said major corrugations to form a contiguous configuration of uniform cross section.

9. A wall structure for a railway car comprising a plurality of metallic plates secured together along vertical lines, each plate having a plurality of major and minor vertical corrugations terminating within the plate, said major corrugations decreasing in width from adjacent one of their ends toward their ends, said minor corrugations positioned between the major corrugations merging from the plane of the plate, and increasing in depth and width until they merge with the major corrugations to form a contiguous configuration of uniform cross section.

10. A metallic plate wall structure provided with a plurality of major vertical corrugations spaced apart distances equal to their width which decrease in width toward their ends, and a plurality of minor vertical corrugations lying between said major corrugations which increase in width toward the edges of the plate until said major and minor corrugations are spaced apart distances equal to their width, the maximum strength of the corrugated wall being below the middle of the major corrugations.

11. A metallic plate wall structure pro-

vided with a plurality of major vertical corrugations symmetrical in cross section about a line midway between the outermost portions of the corrugations which decrease in width toward their ends, and a plurality of minor vertical corrugations lying between said major corrugations which increase in width toward the edges of the plate until they form a cross section symmetrical about a line midway between the outermost portions of the corrugations, the maximum strength of the corrugated wall being below the middle of the major corrugations.

12. A wall for a railway car comprising a metallic plate secured to oppositely disposed horizontal frame members of the car, said plate provided with a plurality of vertical major corrugations which decrease in width toward their ends, said major corrugations having their maximum width adjacent the lower frame member, each plate also provided with a plurality of minor corrugations lying between said major corrugations, which increase in width toward the edges of the plate until the major and minor corrugations terminate in the plate adjacent said oppositely disposed frame members and in line with each other.

13. A wall for a railway car comprising a metallic plate secured to oppositely disposed horizontal frame members of the car, said plate provided with a plurality of vertical major corrugations which decrease in width toward their ends, said major corrugations having their maximum width adjacent the lower frame member, each plate also provided with a plurality of minor corrugations lying between said major corrugations, which increase in width and in depth toward the edges of the plate until the major and minor corrugations terminate in the plate adjacent said oppositely disposed frame members and in line with each other.

14. A wall for a railway car comprising a metallic plate secured to oppositely disposed horizontal frame members of the car, said plate provided with a plurality of vertical major corrugations spaced apart distances substantially equal to their width which decrease in width toward their ends where they merge into the plate adjacent said frame members, said major corrugations having their maximum width adjacent the lower frame member, each plate also provided with a plurality of minor corrugations lying between said major corrugations which increase in width toward the edges of the plate until the major and minor corrugations are spaced apart distances equal to their width adjacent said oppositely disposed frame members.

15. A wall for a railway car comprising a metallic plate secured to oppositely disposed horizontal frame members of the car, said plate provided with a plurality of vertical major corrugations spaced apart distances

- substantially equal to their width which decrease in width toward their ends where they merge into the plate adjacent said frame members, said major corrugations having their maximum width adjacent the lower frame member, each plate also provided with a plurality of minor corrugations lying between said major corrugations which increase in width and in depth toward the edges of the plate until the major and minor corrugations are spaced apart distances equal to their width adjacent said oppositely disposed frame members. 10 until the major and minor corrugations are 65 contiguous and form a sinuous configuration adjacent said oppositely disposed frame members.
16. A wall for railway car comprising a metallic plate secured to oppositely disposed horizontal frame members of the car, said plate provided with a plurality of vertical major corrugations symmetrical in cross section about a line midway between the outermost portions of the major corrugations which decrease in width toward their ends where they merge into the plate adjacent said frame members, said major corrugations having their maximum width adjacent the lower frame member, each plate also provided with a plurality of minor corrugations lying between said major corrugations which increase in width until the major and minor corrugations form a cross section symmetrical about a line midway between the outermost portions of the corrugations adjacent said oppositely disposed frame members. 20
17. A wall for a railway car comprising a metallic plate secured to oppositely disposed horizontal frame members of the car, said plate provided with a plurality of vertical major corrugations symmetrical in cross section about a line midway between the outermost portions of the major corrugations which decrease in width toward their ends where they merge into the plate adjacent said frame members, said major corrugations having their maximum width adjacent the lower frame member, each plate also provided with a plurality of minor corrugations lying between said major corrugations which increase in width toward the edges of the plate until the major and minor corrugations are spaced apart distances equal to their width and form a cross section symmetrical about a line midway between the outermost portions of the corrugations adjacent said oppositely disposed frame members. 30
18. A wall for a railway car comprising a metallic plate secured to oppositely disposed horizontal frame members of the car, said plate provided with a plurality of vertical truncated major corrugations which decrease in width toward their ends where they merge into the plate adjacent said frame members, said major corrugations having their maximum width adjacent the lower frame member, each plate also provided with a plurality of minor corrugations lying between said major corrugations which increase in width
19. A wall for a railway car comprising a metallic plate secured to oppositely disposed horizontal frame members of the car, said plate provided with a plurality of vertical truncated major corrugations which decrease in width toward their ends where they merge into the plate adjacent said frame members, said major corrugations having their maximum width adjacent the lower frame member, each plate also provided with a plurality of minor corrugations lying between said major corrugations which increase in width and in depth until the major and minor corrugations are contiguous and form a sinuous configuration adjacent said oppositely disposed frame members. 70
20. A wall for a railway car comprising a metallic plate secured to oppositely disposed horizontal frame members of the car, said plate provided with a plurality of vertical major corrugations spaced apart distances substantially equal to their width symmetrical in cross section about a line midway between the outermost portions of the major corrugations which decrease in width toward their ends where they merge into the plate adjacent said frame members, said major corrugations having their maximum width adjacent the lower frame member, each plate also provided with a plurality of minor corrugations lying between said major corrugations which increase in width toward the edges of the plate until the major and minor corrugations are spaced apart distances equal to their width and form a cross section symmetrical about a line midway between the outermost portions of the corrugations adjacent said oppositely disposed frame members. 80
21. A metallic structure for a railway car, comprising a metallic plate secured to oppositely disposed frame members of the structure, said plate provided with a plurality of constant depth vertical major corrugations with substantially flat apices with the parts of the plate between the major corrugations also substantially flat, said plate also provided with a plurality of minor corrugations lying substantially between the major corrugations which terminate into the plate adjacent said frame members, substantially in alinement with said major corrugations, where the said major and minor corrugations have arcuate apices and the parts of the plate between the ends of the major and minor corrugations are also of arcuate configuration. 90
22. A wall structure for a railway car comprising a metallic plate secured to upper and lower frame members of the car provided

with a plurality of varying width vertical major corrugations and a pair of aligned varying width vertical minor corrugations positioned between adjacent major corrugations, the maximum strength of the corrugated wall being nearer said lower frame member than said upper frame member.

23. A metallic plate provided with a plurality of varying width vertical major corrugations and a pair of aligned varying width vertical minor corrugations positioned between adjacent major corrugations, the maximum strength of the corrugated wall being

below the middle of the corrugated portion of the plate.

24. A metallic plate provided with a plurality of varying width vertical major corrugations and a pair of aligned varying width vertical minor corrugations positioned between adjacent major corrugations, having the upper minor corrugations longer than the lower minor corrugations, the maximum strength of the corrugated wall being below the middle of the corrugated portion of the plate.

ARTHUR E. SMALL.
